(57) **CLAIM**

The ornamental design for a display screen with graphical user interface, as shown and described.

DESCRIPTION

FIG. 1 is a perspective view of a display screen with graphical user interface;

FIG. 2 is a front view thereof;

FIG. 3 is a second embodiment thereof;

FIG. 4 is a third embodiment thereof;

FIG. 5 is a fourth embodiment thereof;

FIG. 6 is a fifth embodiment thereof; and,

FIG. 7 is a sixth embodiment thereof.

The broken line showing an electronic device illustrate environmental subject matter; whereas the broken line showing a display screen illustrate portions of the article. The subject matters depicted in broken lines do not form part of the claimed design.

1 Claim, 7 Drawing Sheets(56)
